G. W. BERRY,
COMBINATION CIGAR CUTTER, MATCH EJECTOR, AND INDICATOR.
APPLICATION FILED MAY 8, 1917.

1,238,381.

Patented Aug. 28, 1917.

INVENTOR.
GEO. W. BERRY
By his Atty. John Q. Seifert

UNITED STATES PATENT OFFICE.

GEORGE W. BERRY, OF ROSE BAY, NEW SOUTH WALES, AUSTRALIA.

COMBINATION CIGAR-CUTTER, MATCH-EJECTOR, AND INDICATOR.

1,238,381.

Specification of Letters Patent. Patented Aug. 28, 1917.

Application filed May 8, 1917. Serial No. 167,349.

To all whom it may concern:

Be it known that I, GEORGE WILLIAM BERRY, a subject of the King of Great Britain, residing at Lorna Doone, Old South

5 Head Road, Rose Bay, in the State of New South Wales, Commonwealth of Australia, have invented certain new and useful Improvements in Combination Cigar-Cutters, Match-Ejectors, and Indicators, of which 10 the following is a specification.

This invention relates to an improved combination cigar cutter, match ejector and indicator and it has been devised particularly for the purpose of providing simple 15 and efficient means whereby the end of a cigar can be easily and quickly cut, a match simultaneously ejected to a point where it can be conveniently grasped and an advertisement displayed conspicuously.

20 A contrivance possessing the features of utility above described will be of great convenience to tobacco smokers and will be exceedingly useful as a medium through which the attention of customers and others may 25 be directed to the price, quality or kind of goods or the like dealt in by a shop-keeper or other person in business.

In order that the invention may be readily understood reference will now be had 30 to the accompanying sheet of explanatory drawings, wherein

Figure 1 is a view in perspective of the invention, and

Fig. 2 is a view in sectional side elevation 35 of Fig. 1.

In these drawings like characters of reference have been employed to indicate similar parts in the different views and the letter *a* designates a casing of rectangular 40 form having its front upper corner rounded off concentrically with a cylinder or roller *b*. The cylinder or roller *b* is provided with end journals *c* which are mounted revolvably in the sides of the casing *a*. If preferred the cylinder or roller can be mounted 45 revolvably on a through spindle having its ends fitted to the casing. The casing can be secured to a counter or other convenient place by means of screws *a*¹ which pass 50 through lugs *a*² formed on the sides of said casing.

A ratchet *d* is fitted to one end of the cylinder or roller and engaging with the ratchet is a pawl *e* which is pivoted to a 55 depressible lever *f* having its inner end fitted

to a rocking spindle *g* mounted transversely in the casing below the said cylinder or roller.

The pawl *e* is kept in engagement with the ratchet *d* by means of a spring *h* or by 60 weighting the lower end thereof in an approved way.

The forward end of the lever *f* projects through a slot *i* formed vertically in the front of the casing and is broadened to form 65 a finger-piece of convenient size and shape.

The periphery of the cylinder or roller is covered with advertisements arranged in such a way that each operation of the lever *f* will cause the cylinder or roller to rotate 70 sufficiently to display a fresh advertisement behind an opening *j* formed in the casing. The opening *j* in the casing can be covered with glass or other transparent material to prevent the ingress of dust to the casing. 75

The advertisements preferably are arranged lengthwise on the cylinder or roller and in order to insure them registering correctly with the opening *j* two control arms *k* and *l* are fitted to the rocking spindle *g*. 80 When the lever *f* is depressed the arm *l* is forced upward into engagement with the teeth on the rear of the ratchet *d* and thereby prevents its further rotation.

When the lever *f* commences to return to 85 its normal position the arm *l* is moved away from the ratchet and when the said lever is completing its return movement the arm *k* is placed in engagement with the teeth on the forward and underside of the ratchet *d* 90 thereby stopping its further rotation.

The pawl can be arranged to move over one or more teeth on the ratchet at each operation according to the size of the latter and the width of the advertisement on the 95 cylinder or roller.

A jaw *m* projects forwardly from about the center of the rocking spindle *g* and engages a rearwardly projecting portion *n* of a cutter plate *o* which is mounted slidably 100 in guides *p* fitted within the front of the casing. The cutter plate *g* is reciprocated by depressing the lever *f* and if preferred the said plate can be operatively connected to the rocking spindle by means other than 105 the jaw *m* and rearward projection *n*.

When the cutter plate *o* is in its normal or raised position a hole *q* therein is in register with a hole *r* in the front of the casing and both of these holes *q* and *r* are flared out- 110

wardly in opposite directions to form cutting edges as shown in Fig. 2 of the drawings.

When it is desired to sever the rolled end 5 of a cigar it is inserted into the hole r and the lever f depressed. The severed end of the cigar falls into a chute s which directs it into a tray or drawer t in the bottom of the casing. The tray or drawer t is inserted 10 into the casing through an opening in the side thereof and it can be withdrawn conveniently for the purpose of emptying the contents when desired.

When the lever f is released the cutter 15 plate o and the other operative parts of the apparatus are returned to their normal position by means of a spring u which is secured to the bottom of the casing and bears against the underside of the said cutter plate as 20 shown in Fig. 2 of the drawings. It will be obvious that the operative parts can be returned to their normal positions by a spring or springs arranged in a variety of different ways.

25 A pair of arms v are fitted to and project rearwardly from the rocking spindle g and the rear ends of said arms v bear upon the underside of or are otherwise operatively connected to the lower end of a match agitating and delivering plate or slide w . The 30 plate or slide w is mounted in guides w^1 arranged in line with the rearwardly inclined front of a match containing receptacle x formed partly within and partly 35 above the rear part of the casing with the bottom inclining downward toward the front to direct the matches in the receptacle toward the plate or slide w .

The upper end of the plate or slide w is 40 rounded at w^2 and beneath the said rounded portion is a horizontal slot w^3 which is large enough to accommodate a single match but not large enough to accommodate two matches, the bottom wall of the slot w^3 being inclined at the same angle as the bottom of the receptacle, and the plate normally occupying a position with the bottom wall of the slot in line with the bottom of the receptacle, as shown in Fig. 2.

45 When the plate or slide w is thrust upwardly by the operation of the lever f a match gravitates into the slot w^3 and is carried upwardly therein until it is opposite an opening or slot w^4 in the front of the 50 match receptacle through which it gravitates into a tray w^5 formed on the front of the receptacle, the bottom wall of the slot w^4 also being inclined at the same angle as the bottom wall of slot w^3 and the bottom of the receptacle. The inclining of the bottom wall of the slots in the plate and receptacle facilitates the gravitation of a match into the slide slot and from said slot through the receptacle slot w^4 .

60 65 The operation of the plate or slide w agi-

tates the matches in the receptacle and tends to bring them all into alinement to facilitate their entrance to the slot w^3 in the said plate or slide and their conveyance to the tray w^5 .

70 The lower end of the plate or slide w is fitted with a spring y which is adapted to bear against an abutment y^1 on the front wall of the receptacle x when the said plate or slide is completing its upward travel. 75 The object of the spring is to provide a buffer action to prevent any jar or knock when the plate or slide is completing its upward travel and in order to insure the match passing correctly from the slot w^3 to the 80 tray w^5 . The spring y also prevents the plate or slide w jamming when in its raised position.

85 The receptacle x for the matches is open at the top and is provided with a slide x^1 or hinged cover of approved design.

90 The top or other approved part of the casing is provided with means for holding a removable piece of material z upon which the matches can be struck. The said means may comprise a guide z^1 , a clamping plate z^2 and a screw z^3 constructed and arranged as shown in Fig. 1 of the drawings.

95 It will be readily understood that the invention may be modified in a variety of ways without departing from the spirit and scope of the same and that it can be designed to eject tooth picks, drinking straws and other small articles of a like nature and simultaneously display advertisements. 100

What I do claim is:

1. A device of the class described comprising the combination with a casing having an opening therein for the reception of a cigar end, a cutter mechanism including a sliding cutter arranged in the rear of such opening, a match carrying receptacle carried by the casing and having a transverse slot therein above the casing, and a sliding ejector in said receptacle operable to eject a match from the receptacle through the slot therein, of means to simultaneously operate the cutter and the match ejector, said means comprising a rockable spindle mounted transversely in the casing, an operating lever fixed to and extending forwardly from said spindle, arms fixed to and extending rearwardly from said spindle and engaging the lower edge of said ejector, a rearwardly extending projection on said cutter, and jaws fixed to and extending forwardly from said spindle and between which said projection is positioned. 110

115 2. A device of the class described comprising the combination with a casing having a transverse opening therein, a cylinder rotatably mounted in the casing with a portion thereof exposed through the opening in the casing, a match carrying receptacle carried by the casing and having a trans-

verse slot therein above the casing, and a sliding ejector in said receptacle operable to eject a match from the receptacle through the slot therein, of means to simultaneously 5 operate the match ejector and impart a predetermined rotative movement to the cylinder, said means comprising a spindle rockably mounted transversely in said casing below the cylinder and the match receptacle, 10 arms fixed to and extending rearwardly from said spindle and engaging the lower edge of said ejector, an operating lever fixed to and extending forwardly from said spindle, a ratchet for said cylinder, a pawl attached 15 to said lever and engaging said ratchet, and spaced stop arms for said cylinder fixed to said spindle and alternately engaging said ratchet.

3. A device of the class described comprising the combination with a casing having a transverse opening therein and an opening therein for the reception of a cigar end, cutter mechanism including a sliding cutter arranged in the rear of the latter opening, 20 a cylinder rotatably mounted in the casing with a portion thereof exposed through the transverse opening in the casing, a match carrying receptacle carried by the casing 25

and having a transverse slot therein above the casing, and a sliding ejector in said receptacle operable to eject a match from the receptacle through the slot therein, of means to simultaneously operate the match ejector and the cutter and to impart a predetermined rotative movement to the cylinder, said 30 means comprising a spindle rockably mounted transversely in said casing below said cylinder and said match receptacle, an operating lever fixed to and extending forwardly from said spindle, a ratchet for said 35 cylinder, a pawl attached to said lever and engaging said ratchet, arms fixed to and extending rearwardly from said spindle and engaging the lower edge of said ejector, a rearwardly extending projection on said 40 cutter, and jaws fixed to and extending forwardly of said spindle between which jaws said projection is positioned.

In witness whereof I have signed this specification in the presence of two witnesses. 45

GEO. W. BERRY.
